UNITED STATES PATENT OFFICE.

WALTER J. HYMAN, OF MONTREAL, QUEBEC, CANADA.

METHOD OF MAKING SIDE BEARINGS.

Application filed April 17, 1922. Serial No. 554,276.

This invention relates to improvements in forged side bearings for railway cars and process of making the same and similar articles. The object of the invention is to provide a process by which side bearings and similar articles may be made inexpensively and quickly by forging instead of by casting, as has been the practice heretofore. A further object is to provide a forged side bearing which will be lighter in weight, stronger and more durable than the cast bearings at present used.

According to this invention, a blank of dish or bowl shape is first produced, and is then deepened and elongated to substantially rectangular form, and the rim portion of the blank set at an inclination to the axis of the central part. The blank thus shaped is finally trimmed to the desired size, and is ready for use. A filler, which may be either cast or drop-forged is provided to form a tread for the rollers.

In the drawings which illustrate the invention

Fig. 1 is a plan view of a blank used, from which to make the side bearing.

Fig. 2 is a sectional view on the line 2—2 of Fig. 1 of such a blank.

Fig. 3 is a plan view of a blank after the first operation.

Figs. 4 and 5 are sections on the lines 4—4 and 5—5 respectively of Fig. 3.

Figs. 6 and 7 are cross-sections corresponding to Figs. 4 and 5 respectively, showing the form of the blank after the next operation.

Fig. 8 is a plan view of a completed side bearing body.

Figs. 9 and 10 are sections on the lines 9—9 and 10—10 respectively of Fig. 8.

Fig. 11 is a view corresponding to Fig. 10 and illustrates a slight modification.

Fig. 12 is a longitudinal section of a filler for the body.

Fig. 13 is a cross-sectional view of the filler.

Referring more particularly to the drawings, 21 designates a dished or bowl shaped blank, preferably circular in form. This blank may be produced in any way that is desirable or expedient, for example, by pressing a plate, but preferably by forging or piercing a solid billet of much smaller diameter and greater thickness than the blank illustrated in Figs. 1 and 2.

The blank is preferably of the circular

form shown, for the reason that it may be more easily forged to this shape and also because the circular shape ensures uniformity of wall thickness and freedom from internal stresses.

The rough blank thus formed is heated and subjected to a flattening operation by means of suitable dies. At the same time, it receives a drawing, which transforms the circular inclined or frusto-conical wall 22 of the rough blank into a substantially vertical wall, as indicated at 23, Figs. 4 and 5, enclosing a rectangular space, as illustrated in Fig. 3. The dished shape of the central part of the blank is not, during this operation, materially changed, as will be clearly seen. It will be noted that the flattening operation has the effect of drawing in diametrically opposite portions of the rim of the rough blank, so that it now presents four roughly formed lugs 24, or projections at the corners of the blank. This flattening and drawing may be done in as many operations as are found necessary, but the step is preferably performed in a single operation.

The next step in the process is what may be termed the second flattening step, and embraces the flattening of the bottom, as indicated at 25, Figs. 6 and 7, and also in effecting a marked change in the upper part of the body and the flange or rim of the blank. The upper part of the body or flange designated 26, has originally an inclination of about 45° to the axis of the blank, and is of a general frusto-conical or frusto-pyramidal form, as will be evident from Figs. 1—5. In the second flattening operation, the angle of this flange is changed, so that it lies roughly at 30° to the axis of the blank, as will be clearly seen at 27, Figs. 6 and 7. This change in angle results in a slight contraction of the circumference. At the same time that the contraction of the circumference is effected, the upper or marginal part of the flange is turned sharply outward as at 28, Figs. 6 and 7. Owing to the fact that this outward turn takes place simultaneously with the contraction of the lower part, comparatively little stress is imposed on the material. It will be observed that in this second flattening step, the flange is changed from its frusto-conical or frusto-pyramidal form to the form of a flat sheet occupying a plane out of normal to the axis of the blank, and inclining transversely of

the blank. The second flattening may be performed in as many operations as desired, but is preferably formed with one operation and one heating of the blank. As a matter of fact, if the dies which perform the first flattening operation have not chilled the material too much, it might be possible to perform the second stamping or flattening without re-heating the blank.

10. The next step in the process is that of finally forming the blank by cutting out the bottom, as indicated at 29, Fig. 8, and trimming the flange 28 to the shape shown. In the cutting out operation of this step, the whole width of the bottom is not cut away, but retaining flanges 30 for the rollers, are allowed to remain at the sides or long edges of the rectangular body. During the cutting out operation, a small portion of the ends or shorter sides of the body are cut away, as indicated at 31, Fig. 9, so as to permit maximum travel of the rollers. During the trimming to shape, the four lugs which were rough formed in the first flattening process, become clearly defined and are also provided with apertures 32 for the passage of fastening means.

15. A somewhat stronger structure may be made by cutting away less of the bottom and turning the material which is allowed to remain, upwardly against the side edges of the body, as shown at 33, Fig. 11. This arrangement doubles the thickness of metal at the edges of the roller opening, and also provides a greater depth of metal under the roller trunnions.

20. A filler shown in Figs. 12 and 13 is provided to occupy the upper or frusto-pyramidal portion of the body. This filler, designated 34, is provided with a bottom, 35, designed when the filler is in place to occupy a plane parallel with the body bottom, while the sides 36 and ends 37 are of different

or varying heights, so that their upper edges occupy the plane of the flange 28. The filler 45 may be stiffened by internal ribs 38. This filler may be formed by drop forging, casting or in any other suitable way.

25. From the foregoing description, it will be readily seen that a finished bearing body 50 may be produced in four main steps from a billet. It will also be seen that each one of these steps is in itself a simple and readily performed operation, but that there is produced by them a progressive change in 55. shape, resulting finally in the completed article, with walls of substantially uniform thickness throughout, and free from internal stresses, cracks or wrinkles. The finished bearing body is much stronger and also 60 much lighter than the cast bearing, and may be produced at an equal or lower cost in an efficient plant.

30. Having thus described my invention, what I claim is:—

65. A process of manufacturing side bearings for railway cars which consists in producing a dish shaped blank substantially frusto-conical in cross section, flattening and simultaneously drawing said blank to transform the frusto-conical wall portion between the rim and the central portion into a substantially vertical wall in such manner that diametrically opposite portions of the rim are simultaneously drawn inwardly to produce roughly formed lugs at the corner of the blank subjecting said blank to a subsequent flattening operation serving to flatten the central portion of the blank and to simultaneously transform the rim of the 70 blank into a flat sheet disposed to occupy a plane out of normal to the central axis of the blank and inclined transversely thereto.

75. In witness whereof I have hereunto set my hand.

WALTER J. HYMAN.
